[57] CLAIM

The ornamental design for a measuring tape, as shown and described.

DESCRIPTION

FIG. 1 is a top, front and left side perspective view of a measuring tape showing our new design;

FIG. 2 is a left side elevational view;

FIG. 3 is a top plan view;

FIG. 4 is a rear elevational view;

FIG. 5 is a front elevational view;

FIG. 6 is a bottom plan view;

FIG. 7 is a right side elevational view;

FIG. 8 is a top, front and left side perspective view of another embodiment of FIGS. 1-7;

FIG. 9 is a left side elevational view;

FIG. 10 is a top plan view;

FIG. 11 is a rear elevational view;

FIG. 12 is a front elevational view;

FIG. 13 is a bottom plan view; and

FIG. 14 is a right side elevational view thereof.
